PRESTRESSING REINFORCED CONCRETE

Herman Schorer, Valhalla, N. Y.

Application February 21, 1940, Serial No. 320,028

11 Claims. (Cl. 72—128)

The present invention relates to means for pre-stressing or applying initial compression on reinforced concrete, more particularly to a prestressing unit by means of which initial compression can be applied to monolithic reinforced concrete structures of any size and configuration during the construction process.

Various methods and means have been devised for subjecting concrete to initial compression for the purpose of reducing or eliminating tensile stresses in the concrete. The prior art methods and means include deformation of the moulds and thereby compressing the concrete in the mould while the concrete hardens and/or applying initial tension forces to the reinforcing steel and maintaining such forces until the concrete has hardened and then releasing said forces and thereby transmitting them to the adjacent concrete and setting up compression therein. With some of the prior art methods the bond between the reinforcements and the concrete is destroyed and monolithic action is not possible. Due to the fact that the reactions of the tensioning forces are generally transmitted to the moulds the methods and devices proposed so far are expensive and their application is limited to the manufacture of comparatively small prefabricated concrete elements, such as beams, slabs, piles, pipes, etc.

It is an object of the present invention to provide a self-contained prestressing device which is independent of the mould and which can be prefabricated in individual units of suitable sizes which can be incorporated in the field in the concrete to be reinforced and prestressed to form a monolithic structure therewith. The units according to the invention can be used in connection with monolithic concrete structures of any outside configuration and can be embedded in said structures wherever precompression is most desirable, i. e., preferably in such parts of the concrete where later on, when the concrete is in actual use, tensile stresses occur. The self-contained prestressable reinforcing units according to the present invention can be manufactured in standardized sizes and conveniently shipped in disassembled or assembled condition. Their application is much more general than that of conventional methods and devices.

Further and other objects of the present invention will be hereinafter set forth in the accompanying specification and claims and shown in the drawings which, by way of illustration, show what I now consider to be preferred embodiments of my invention.

In the drawings:

Figure 1 is a side view of the precompressing and prestressing unit according to the present invention.

5 Figure 2 is a cross sectional view of the unit shown in Figure 1 and taken along line II—II of Figure 1.

Figure 3 is an end view of the unit shown in Figure 1.

10 Figure 4 is a part sectional view of the unit according to the present invention embedded in concrete and in normal operating condition.

Figure 5 is a side view of a modified precompressing unit according to the present invention.

15 Figure 6 is a side view of a modified spacer according to the present invention.

Figure 7 is a side view of a wire contracting member used in the unit according to Figure 5.

20 Figure 8 is a longitudinal sectional view of a modified wire stretching end member.

Figure 9 is a part cross sectional and part end view of the member illustrated in Figure 8 and taken along line IX—IX of said figure.

25 Figure 10 is a constructional concrete element reinforced and precompressed according to the present invention.

Figure 11 is a cross sectional view of the element shown in Figure 10 and taken along line XI—XI in said figure.

30 Figure 12 is a cross sectional view of the element shown in Figure 10 and taken along line XII—XII in said figure.

Like parts are designated by like numerals in all figures of the drawing.

35 Referring more particularly to Figures 1 to 4, 1 designates a longitudinal compression member, such as a steel rod of great strength which passes through the center of the spacing members 2 which are disposed along the rod at regular intervals. Member 1 which, in case of larger units,

40 may consist of a plurality of rods or the like, is enclosed in a thin walled tube or sheath 10 made of paraffined paper or similar material. The purpose of this tube is to prevent mortar from bonding with the compression rod 1, and to permit sliding of the rod within tube and spacers. The spacers may consist of cast iron, tile or pre-cast concrete blocks, having surfaces that will provide adequate bond when embedded in mortar.

45 Tension means 3 and 4 in the form of thin high strength steel wires are disposed around center rod 1 and placed substantially over the periphery of the spacers 2. Two substantially like sets of tension means are provided which are wound in 50 steep helices and in opposite direction around

55

the column formed by the center member 1 and the spacers 2. Guide grooves or recesses 20 and projections 21 are provided on the spacers 2 for keeping the wires 3 and 4 apart and preventing direct intersection of and kinks in the wires.

The ends of the wires are pairwise interconnected and form loops around the lugs 6 projecting from a nut member 5. A bolt 7 is screwed into the nut member 5 and is provided with a cavity 8 at its threaded end for receiving the 10 end of compression member 1. A steel ball 9 may be inserted in the cavity 8 for reducing friction between rod 1 and bolt 7 and torsion when bolt 7 is tightened. After assembling the pre-stressing unit bolt 7 is screwed into nut member 5 until tension wires 3 and 4 are uniformly pre-stressed to the desired extent. The reaction of 15 the combined tensile forces is transmitted to the compression member 1 by means of the bolt 7 and the steel ball 9.

A tensioning mechanism as described in the paragraph next above may be provided at each end or at one end only of the prestressing unit. In the latter case an end or anchorage member is provided at one end of the unit as shown at the left side of Figure 1. The wires 3 and 4 form loops around the lugs 6' projecting from the end block 5'. Block 5' is provided with a cavity 8'' holding a ball 9'' against which the center rod 1 abuts.

Warping or buckling of the compression member 1, in spite of the relatively high compressive stress in said member, is prevented by the spacers 2 which act as elastic supports due to the radial force effect produced by the tension members 3 and 4. Torsional forces on the end supports composed of parts 5, 6, and 7 or 5' and 6' are absent on account of the two series of tension windings arranged in opposite directions. Theoretical considerations as well as practical experience prove that, already with a rather steep pitch of the windings of means 3 and 4, the necessary stability can be obtained also under extreme stress conditions. The assembled and tensioned unit according to the present invention may be bent to form a flat curve and will snap back into a straight line as soon as the external bending forces are removed.

A modification of the prestressed unit according to the present invention is shown in Figures 5 to 8. Instead of a single central compression member 1 a compression member 20 is provided composed of a plurality of rods 21 disposed parallel to one another and held together by means of cuff members 22. To prevent mortar from bonding with the compression member 20, said member is surrounded by means of tubes 10' made of paraffined paper or the like. Instead of two sets of helical wires 3 and 4, a plurality of wires 23 are arranged in planes radiating from the central member 20. The wires 23 are spaced from the central member by means of spacers 24, illustrated in Figure 6, which have a rounded axial outer contour 25 to avoid sharp bends in the wires and which have diametrically opposite projections 26 to keep the wires apart and pairwise in diametrical planes.

The distances from the center of the spacer of the axially curved outer surfaces of the recesses between the projections 26 may alternately be different so that the spacers according to Figures 5 and 6 can also be used for producing a unit according to Figure 1 instead of the spacers of the type shown in Figures 1 and 2. Undesired contact of the wires of the two sets

5 of wires wound in opposite direction is avoided by placing the wires of one set over the surfaces 44 on the larger diameter and the wires of the other set over the surfaces 45 on the smaller diameter.

Between two spacing members 24 a wheel like contracting member 27 made according to Figure 7 is arranged. Member 27 has openings 28 through which pass the wires 23 and which openings are disposed on smaller diameters than the outer and wire supporting surface of the spacers 24. Upon stretching of the wires 23 the same are firmly pulled in radial direction and pressed to the outer surfaces of the spacers 24, by means of members 27 and the whole structure props up the central member and stiffens the unit against lateral deviations.

For stretching wires 23 and transferring the tension reaction forces as compressing forces to 20 the central member 20 an end unit may be used as shown on the right hand side of Figure 1. For larger units a mechanism as shown on the right hand side of Figure 5 and in Figures 8 and 9 may be preferable. The mechanism consists of a central member 29 of angular cross sectional configurations and having flanges 30 and 31. The tension wires 23 enter the structure through flared openings 32 in flange 31 and pairwise run along the knurled surfaces 33 and individually 25 into the holes 34 in flange 30. They are firmly and preliminarily held in said holes by means of screws 35. After preliminary tensioning and correct setting of wires 23 and the whole unit, cover plates 36 having knurled surfaces 37 corresponding to the surfaces 33 are pressed onto 30 the wires 23 by means of bolts 38 so that the wires are inescapably held in the stretching end unit. An end plate 39 is placed in a recess at the left end of member 29 and firmly held thereto by means of bolts 40. The central member 20 passes through a bore 41 in plate 39 into the interior 42 of member 29 and is held in correct 35 position by means of plate 39. At the other end of member 29 an interior thread is provided for the threaded bolt 43. This bolt is the equivalent to bolt 7 and its end is also provided with a cavity 8' containing a ball 9' for insertion of and abutting cooperation with one end of the compression member 20. At the other end of member 20 the 40 same stretching mechanism as shown in Figure 5 or an end unit of the type shown on the left hand side of Figure 1 may be used.

The assembled units according to the present invention are placed into the moulds for the concrete work as are conventional reinforcing rods and the like with the difference that the end supports project from the mould and remain outside of the form boards 11. The concrete is placed into the forms according to good current practice, thoroughly spaded and compacted until the tension members, spacers and tubes surrounding the central compression members become completely imbedded in mortar.

After the concrete has reached the desired compressive strength, the boards 11 are removed. By releasing the bolts 7 or 43 the compressive force in members 1 or 20 is gradually transferred to the concrete. The end supports are removed and the tension wires are cut along the exterior face of the concrete. The compression members may also be cut and left in place or may be pulled out for reuse. The tube section near the face of the concrete is removed and the small holes are closed with a stiff mortar. Rusting at the end 50 of the tension wires is prevented by rubbing the

concrete face with cement mortar or by the application of a thin plaster coat 12. Under certain conditions it may be advantageous to place the end support nut 5 or the unit 29, 36 inside the form and to leave it embedded in concrete for end anchorage of the tension wires.

After releasing the compression member the initial tension in the members 3 and 4 is somewhat reduced due to the elastic and plastic deformation and shrinkage of the concrete, the proportion depending on the amount of prestress. The balance is available for the initial compression of the concrete. The design and proper arrangement of the prestressed reinforcing units permits the complete elimination of all tensile stresses in the concrete also under extreme load conditions.

Figures 10 to 12 show the application of prestressed reinforcing units according to the invention to the construction of a concrete girder 17. The units 13, 14 and 15 are placed in a longitudinal direction, so as to cause maximum compression at the bottom of the girder near the center of the span 18 and nearly uniform compression over the end faces 19. For this purpose units 13 and 15 are placed along the top and bottom side of the girder respectively. Units 14 follow the bottom of the girder near the center portion and are curved upward toward the ends of the girder. The prestressed vertical units 16 which are arranged closer together at the end portion of the girder compress the concrete also in vertical direction. In this manner the so-called diagonal tension can be effectively eliminated. The usual consideration of shearing stresses no longer presents a limiting factor in a structure prestressed according to the present invention.

If desired, the holes left by the removed compression members 1 can be utilized for drainage, electric conduits, heating or cooling purposes, etc.

While I believe the above described embodiments of my invention to be preferred embodiments, I wish it to be understood that I do not desire to be limited to the exact details of design and construction shown and described, for obvious modifications will occur to a person skilled in the art.

What is claimed is:

1. A self-contained precompressing mechanism for subjecting concrete to internal compression, comprising a stretching mechanism, a longitudinal compression member having ends abutting said stretching mechanism, separating means interposed between said compression member and the concrete and adapted to definitely prevent binding of the concrete to said compression member, and a plurality of longitudinal tension members disposed symmetrically around said compression member and having their ends connected to said stretching mechanism, said stretching mechanism stretching said tension members and transmitting the stretching force reaction thereof to said compression member.

2. A self-contained precompressing mechanism for concrete, comprising a stretching mechanism including operable means and anchorage means, a rodlike central compression member having ends individually abutting said operable means and said anchorage means, sheath means enclosing said compression member, said compression member being slideably movable in said sheath means, and a plurality of wirelike tension members spaced from and disposed symmetrically around said compression member and having ends

individually connected to said anchorage means and to said operable means.

3. A precompressing reinforcing mechanism for concrete, comprising a central, column-like compression member, a plurality of spacers disposed on said member and being spaced from one another, a plurality of longitudinal tension members disposed symmetrically around said compression member and resting on said spacers and being thereby spaced from said compression member, a stretching mechanism connected to and holding the ends of said tension members and abutting said compression member and adapted to stretch said tension members and simultaneously transmit the stretching force reaction thereof to said compression member.

4. A self-contained reinforcing mechanism for subjecting concrete to permanent internal compression, comprising a central compression member, a plurality of spacers disposed on said member and being equally spaced from one another, two sets of wirelike tension members helically wound in opposite direction around said compression member and resting on said spacers and being spaced thereby from said compression member, an adjustable tension mechanism connected to and holding one end of said tension members, and anchorage means connected to the other end of said tension members, said tensioning mechanism and said anchorage means individually abutting the individual ends of said compression member and exerting a pull on said tension members and simultaneously transmitting the tension force reaction of said tension members to the ends of said compression member.

5. A precompressing reinforcing mechanism for concrete, comprising a central compression member, sheath means loosely surrounding said compression member, a plurality of spacers provided with recesses and projections disposed on said member and being equally spaced from one another by said sheath means, said compression member being freely longitudinally movable inside said sheath means and said spacers, two sets of wirelike tension members wound helically in opposite direction around said compression member and spaced therefrom by means of said spacers, one set of said tension members resting in said recesses and the other set resting on said projections and being separated thereby from one another, and a tensioning mechanism including a nut member connected to one of the ends of said tension members and a bolt member screwed into said nut member and abutting one end of said compression member and anchorage means connected with the other ends of said tension members and abutting the other end of said compression member, said tensioning mechanism tensioning said tension members upon relative motion of said bolt member with respect to said nut member and simultaneously transmitting the tensioning force reaction of said tension members to said compression member.

6. A self-contained prestressing mechanism for concrete comprising a central compression member, a plurality of wheellike spacer members axially slideably disposed on said compression member, tubular sheathing means coaxially and slideably disposed on said compression member and between and spacing said spacer members from one another, two sets of tension wires wound in opposite direction in steep helices around said compression member and being spaced from said member by means of said spacer members, and a tensioning mechanism

including a bolt member having a cavity for receiving one end of said compression member, a ball member disposed in said cavity and affording free rotational movement of said bolt member with respect to said compression member, and including a nut member connected to one of the ends of said tension wires and screwed to said bolt member, anchorage means connected to the other ends of said tension wires and having a cavity and a ball member therein abutting the other end of said compression member, said mechanism affording tensioning of the tension wires before embedding the latter in concrete and transmitting the tension reaction force of said wires to said compression member and releasing the tension force in said tension wires after the concrete has sufficiently hardened, thereby subjecting the adhering concrete to permanent internal compression.

7. A self-contained precompressing reinforcing device for concrete construction, comprising a plurality of rodlike central compression members disposed in substantially parallel relation to one another, a plurality of spacers and contracting members alternately disposed in spaced relation to one another on said compression member, a plurality of wirelike tension members laid over said spacers and extending through said contracting members and disposed symmetrically around said compression member and held in flat angled zig-zag position by said spacers and contracting members, and an end tensioning mechanism interconnecting said tension members and said compression members, said mechanism comprising a hollow central member having an interior thread and an outer surface, a plurality of clamp members having surfaces corresponding to portions of said outer surface and being disposed opposite thereto, said tensioning means extending individually between the surface of said central member and the surfaces of individuals of said clamp members and being firmly clamped to said central member by means of said clamp members, and a threaded bolt member screwed into the interior thread of said central member and abutting said compression member, said tension members being stretched and the stretch reaction thereof being simultaneously transmitted to said compression member upon rotation of said bolt member relatively to said central member.

8. A self-contained precompressing reinforcing device for concrete construction, comprising a rodlike central compression member, a plurality of spacers and contracting members alternately disposed in spaced relation to one another on said compression member, a plurality of wirelike tension members laid over said spacers and extending through said contracting members and disposed symmetrically around said compression member and held in flat angled zig-zag position by said spacers and contracting members, and a tensioning mechanism interconnecting said tension members and said compression member,

5 said mechanism comprising a nutlike member connected with said tension members and a threaded bolt member screwed into said nutlike member and abutting said compression member, said tension members being stretched and the stretch reaction thereof being simultaneously transmitted to said compression member upon rotation of said bolt member relatively to said nutlike member.

10 9. A self-contained precompressing reinforcing device for concrete construction, comprising a central compression member, a plurality of spacer members disposed in spaced relation to one another on said compression member, a plurality of wirelike tension members disposed symmetrically around said compression member and spaced from said compression member by said spacer members, and a tensioning mechanism interconnecting said tension members and said compression member, said mechanism comprising a hollow central member having an interior thread and an outer surface, a plurality of clamp members having surfaces corresponding to portions of said outer surface and being disposed opposite thereto, said tension members extending individually between the surface of said central member and the surfaces of individuals of said clamp members and being firmly clamped to said central member by means of said clamp members, and a threaded bolt member screwed into the interior thread of said central member and abutting said compression member, said tension members being stretched and the stretch reaction thereof being simultaneously transmitted to said compression member upon rotation of said bolt member relatively to said central member.

15 10. A precompressing mechanism for subjecting concrete to internal compression as set forth in claim 1, said compression member being composed of a plurality of individual longitudinal compression elements.

20 11. A prestressed reinforced concrete construction comprising a monolithic mass of concrete, a precompressing mechanism disposed at a portion of said concrete mass subjected to tensile or shearing stresses when in normal use, said mechanism comprising a rodlike compression member removably embedded in the concrete, a plurality of wirelike tension members substantially equally spaced from and disposed substantially symmetrically around said compression member and permanently embedded in said concrete mass and in intimate contact therewith, and a stressing mechanism disposed outside of said concrete mass and abutting one end of said compression member and firmly connected to the ends of said tension members, said tension members being tensioned before the concrete is placed by means of said stressing mechanism and being released and compressing the adhering concrete after the concrete has hardened.

HERMAN SCHORER.
